UNITED STATES PATENT OFFICE.

HUGO C. WELL, OF NEW YORK, N. Y.

INTERNAL-COMBUSTION ENGINE.

1,221,121.

Specification of Letters Patent.

Patented Apr. 3, 1917.

Application filed May 17, 1912, Serial No. 697,852. Renewed May 1, 1915. Serial No. 25,298.

To all whom it may concern:

Be it known that I, HUGO C. WELL, a subject of the German Emperor, and a resident of the city of New York, borough of the Bronx, in the county and State of New York, have invented a new and Improved Internal-Combustion Engine, of which the following is a full, clear, and exact description.

10 My invention relates to engines, and it has for its object to provide one of the internal combustion type which has a piston with a rotatable valve member with a port which is adapted to receive the combustible mixture through a port in the side of the cylinder, the rotatable valve member also having ports which are adapted to register with ports in the piston to permit of a quick circulation of air in the cylinder to cool the cylinder and clear it of all products of combustion.

Other objects of the invention are to direct air to one of the ports in the piston, to lead the air from the other port in the piston and 25 out of the cylinder, and to rotate the valve member in the piston.

Still other objects of the invention will appear in the following complete specification, in which the preferred form of the invention is disclosed.

Certain features of this invention are disclosed in applicant's co-pending application having Serial No. 778,075.

In the drawings similar characters of reference indicate corresponding parts in all the views, in which—

Figure 1 is a sectional elevation of my improved engine;

Fig. 2 is a sectional view on the line 2—2 of Fig. 1;

Fig. 3 is a sectional view on the line 3—3 of Fig. 1; and

Fig. 4 is an enlarged fragmentary sectional view showing how the ratchet teeth 45 are mounted on the piston rod.

In internal combustion engines it is important that the cylinder be thoroughly cooled and cleansed of all products of combustion before the admission of a new charge 50 of the combustible mixture but with the rapid movement of the piston, there is difficulty in clearing the cylinder when only an exhaust valve is provided. My invention includes means for forcing air under pressure 55 through the cylinder after the explosion, and in the preferred embodiment of the inven-

tion, shown in the drawings, this air is led through a port in the piston and out of another port, the ports being commanded by a valve member mounted for rotating on the 60 piston, the valve member also being provided with a port for receiving the combustible mixture from a port in the cylinder, after the ports in the piston have been closed by the said valve member.

The invention is shown in the drawings as applied to a four-cycle engine, the cylinder 5 having an inlet port 6, and the cylinder being also provided with scavenger ports 7 and 8. The scavenger ports 8 are closed 70 at the outer side of the cylinder 5 by a casing member 9, this casing member 9 having a port 10, with which the pipe 11 communicates. The cylinder 5 is provided with an elbow 12 at the port 7, a tube or conduit member 13 being secured to this elbow for communicating with the ports 7. The tube or conduit member 13 is disposed longitudinally of the cylinder 5. In the cylinder 5 there is disposed a piston 14, having ports 15 and 16, which are commanded by the valve member 17, this valve member 17 having ports 18, with which the ports 15 and 16 are adapted 80 to communicate. Integral with the piston 14, there are two conduit members 19 and 20, the conduit member 19 communicating with the port 16, and the conduit member 20 communicating with the port 15. The lower terminal 21 of the conduit member 19 is disposed outwardly, affording communication 90 between the scavenger ports 8 and the conduit 19. The tube or conduit 13 is disposed in and telescopes with the conduit 20. The valve member 17, which is disposed on the piston 14, is connected with a ratchet disk 22 by a stud 23, which is disposed through an orifice 24 in the piston 14. This ratchet disk 22 is disposed at the under side of the piston 14, and is provided for rotating the valve member 17. The valve member 17 has a peripheral rim 25, having ports 26, which are adapted to register with the port 6 in the cylinder, for affording communication between the inlet port 6 and the interior of the cylinder. The piston 14 is connected with the crank 27 by a piston rod 28, in the customary manner. A sleeve 29 has a thread 95 which meshes in a threaded opening 30 in the top of the piston rod 28 for receiving a ratchet tooth 31, which is provided for engaging the ratchet disk 22 at one side of its center. There is a slot 32 in the sleeve 29, in

which is disposed a guide screw or pin 33, which is secured to the ratchet tooth 31, and limits the movement of the said ratchet tooth. The ratchet tooth 31 is held yieldingly extended by a spring 34, which is disposed in the sleeve 29, the face of the upper terminal 35 of the ratchet tooth 31 being disposed obliquely relatively to the sides of the ratchet tooth, so that while it will have a positive movement with the ratchet disk to rotate the valve member 17 in one direction, it will move freely over the ratchet disk in the opposite direction, the spring 34 assisting in this return movement. A pawl 22^a

15 may be provided to prevent the ratchet disk from returning with the ratchet tooth.

While it will be understood that either or both of the ports 15 and 16 in the piston 14 may be used as exhaust ports, I prefer to use 20 the port 15 as an exhaust port, and to use the port 16 as a means of supplying the cylinder with air under pressure, by which means the products of combustion will be quickly driven from the cylinder, and 25 through one of the ports 18 in the valve member 17, the port 15 in the piston 14, the conduit 20, the conduit 13 and the port 7, the pipe 11 being in communication with a supply of air under pressure so that as soon 30 as one of the ports 18 in the valve member 17 registers with the port 16, one of the ports 18 in the valve member 17 registers with the port 15, and the lower terminal 21 of the conduit 19 is in communication with 35 the scavenger ports 8, a supply of air under pressure will be received from the pipe 11 and will be transmitted to the cylinder 5 and out of the cylinder through the conduit 20, the conduit 13 and the port 7. The cylinder 40 is cooled by this circulation of air therethrough.

As will be seen by referring to the drawings the ports will be in this position after the explosion, and with the movement of the 45 piston 14 in the direction of the cylinder head the ports 15 and 16 will be closed by the valve member 17, when the piston is at the end of the return stroke. As the valve member 17 rotates on the piston 14 the port 50 26 will be moved into position to receive the combustible mixture from the port 6 which combustible mixture is compressed by the movement of the piston toward the cylinder head when it is exploded in the usual 55 manner. While I have shown my invention as applied to a four-cycle engine it will be understood that it may be used on other engines.

In the operation of the engine the ratchet 60 tooth 31 moves the ratchet disk 22 and the valve member 17 one-eighth of a revolution at every revolution of the main shaft so that with every second revolution of the main shaft one of the ports 26 will be disposed 65 opposite the port 6. In this way the cylinder

is charged with the combustible mixture with every second revolution of the main shaft and the combustible mixture is compressed and fired as is customary in 4-cycle engines. When the piston is moved down 70 again the main shaft has made a complete revolution and the valve member 17 has made one-eighth of a revolution which has moved two of the ports 18 into communication with the ports 15 and 16 to clean the 75 cylinder of the products of combustion.

Having thus described my invention I claim as new and desire to secure by Letters Patent:

1. In an engine, a cylinder having a port, 80 a conduit disposed in and longitudinally of the cylinder, and communicating with the port, a piston having a port and a conduit communicating with the port, the second-mentioned conduit having a sliding engagement with the first-mentioned conduit, a valve member for commanding the port in the piston, and means for operating the valve member. 85

2. In an engine a cylinder a piston in the 90 cylinder having ports, a valve member for commanding the ports, and means for directing a supply of cleansing fluid into the cylinder through one of the ports for carrying out of the other port the products of 95 combustion.

3. In an engine a cylinder, a piston for moving in the cylinder and being provided with two scavenger ports, a valve member mounted to rotate on the piston for commanding the ports, and means for directing a supply of cleansing fluid into the cylinder through one of the ports, and carrying out of the other port the products of combustion. 100

4. In an engine a cylinder, a piston for reciprocating in the cylinder, and being provided with two scavenger ports, a valve member for commanding the ports, means for directing a supply of cleansing fluid into the cylinder through one of the ports for carrying out of the other port the products of 110 combustion, a piston rod, and means for operating the valve member by the piston rod. 105

5. In an engine, a cylinder having a port, 115 a piston with a port and a valve member mounted to rotate on the piston for commanding the piston port, and having a rim with a port with which the cylinder port is adapted to communicate.

6. In an engine, a cylinder, a piston for reciprocating in the cylinder and provided with a scavenger port, a valve member mounted to rotate on the piston for commanding the scavenger port, a ratchet member mounted to rotate with the valve member, a piston rod connected with the piston and having a sleeve, a ratchet tooth disposed for moving longitudinally in the sleeve and adapted to engage the ratchet member, and 125 130

a spring for holding the ratchet tooth extended.

7. In an engine, a cylinder having a port, a piston with a port and a valve member 5 mounted to move on the piston for commanding the piston port and having a rim with a port with which the cylinder port is adapted to communicate.

8. In an engine, a cylinder having two 10 ports, a conduit disposed in and longitudinally of the cylinder, and communicating with one of the ports, a piston having two ports and two conduits communicating with the piston ports, one of the last-mentioned 15 conduits having a sliding engagement with the first-mentioned conduit, and the other of the second-mentioned conduits having a lateral port for communicating with one of the ports in the cylinder, when the piston 20 in a predetermined position relatively to the cylinder, a valve member for commanding the ports in the piston, and means for operating the valve member.

9. In an engine, a cylinder having two 25 ports, a conduit disposed in and longitudinally of the cylinder, and communicating with one of the ports, a piston having two ports and two conduits communicating with the piston ports, one of the last-mentioned 30 conduits having a sliding engagement with the first-mentioned conduit, and the other of the second-mentioned conduits having a lateral port for communicating with one of the ports in the cylinder, a valve member for 35 commanding the ports in the piston, and means for operating the valve member.

10. In an engine, a cylinder having two ports, a conduit disposed in and longitudinally of the cylinder, and communicating 40 with one of the ports, a piston having two ports and two conduits communicating with the piston ports, one of the last-mentioned conduits having a sliding engagement with the first-mentioned conduit, and the other of 45 the second-mentioned conduits having a lateral port for communicating with one of the ports in the cylinder, when the piston is in a predetermined position relatively to the cylinder, a valve mounted to rotate on 50 the piston for commanding the ports in the piston, and means for rotating the valve.

11. In an engine a cylinder having two scavenger ports, a piston in the cylinder provided with two ports and two conduits 55 communicating with the piston ports, and extending longitudinally of the cylinder for communicating with the first-two-mentioned ports, a valve member for commanding the piston ports, a ratchet member mounted to

rotate the valve member, a piston rod connected with the piston, and a tooth mounted on the piston rod for engaging the ratchet member for operating the valve member.

12. In an engine a cylinder having two 60 scavenger ports, a piston in the cylinder provided with two ports and two conduits communicating with the piston ports, and extending longitudinally of the cylinder for 65 communicating with the first-two-mentioned ports, a valve member for commanding the piston ports, a ratchet member mounted to rotate the valve member, a piston rod, a sleeve secured to the piston rod, a ratchet tooth disposed for moving in the sleeve, and for engaging the ratchet member, 70 and a spring for holding the ratchet tooth 75 extended.

13. In an engine, a cylinder having a port, a piston, a valve member mounted to rotate on the piston and being provided with a rim, 80 with a port with which the cylinder port is adapted to communicate, a ratchet disk for rotating the valve member, a piston rod, and a tooth mounted on the piston rod for 85 engaging and operating the ratchet disk.

14. In an engine, a cylinder having a port, a piston with two scavenger ports, a valve member mounted to rotate on the piston for commanding the scavenger ports, and having a rim with a port with which the cylinder port is adapted to communicate, and 90 means for rotating the valve member.

15. In an internal-combustion engine, a cylinder having a port, a piston for reciprocating in the cylinder, and having a port for 95 communicating with the port of the cylinder, a valve mounted for rotating on the piston for commanding the second mentioned port, a piston rod fulcrumed to the piston, and means connecting the piston rod 100 with the valve for rotating the latter.

16. In an internal combustion engine, a cylinder having a port, a piston for reciprocating in the cylinder and having a port for 105 communicating with the first mentioned port, a valve rotatably mounted on the piston on an axis substantially parallel with the axis of the cylinder for commanding the second mentioned port, and means for operating the valve.

In testimony whereof I have signed my name to this specification in the presence of two subscribing witnesses.
